UNITED STATES PATENT OFFICE.

OTTO JAEGER, OF ELMINS PARK, PENNSYLVANIA.

DISPENSING APPARATUS.

1,199,274.

Specification of Letters Patent. Patented Sept. 26, 1916.

Application filed October 9, 1915. Serial No. 54,965.

To all whom it may concern:

Be it known that I, OTTO JAEGER, a citizen of the United States, residing at Elkins Park, Montgomery county, Pennsylvania,
5 have invented certain new and useful Improvements in Dispensing Apparatus, of which the following is a full, clear, and exact description, reference being had to the accompanying drawings, forming a part of
10 this specification.

The object of my invention is to provide a novel, simple and efficient dispensing apparatus having a container for the articles to be dispensed, movably mounted on a suitable support and provided with means to discharge one or more articles from the container when it is moved on its support, the apparatus being especially adapted for use in dispensing biscuits.

20 With this object in view my invented apparatus consists of the elements and the combinations of them hereinafter fully described and claimed.

In the accompanying drawings, illustrating my invention: Figure 1 is a front elevation of a dispensing apparatus embodying my invention. Fig. 2 is a side elevation thereof. Fig. 3 is a horizontal section through the supporting frame and the article container, on line 3—3 of Fig. 2. Fig. 4 is a horizontal section through the article container and adjuncts, on line 4—4 of Fig. 2. Fig. 5 is a vertical section through the lower portion of the article container showing the plate inserted therein to support the articles during the filling or charging operation. Fig. 6 is a vertical section, on line 6—6 of Fig. 2, showing the connection between the container and the arm which operates the pivoted discharging member. Fig. 7 is a vertical section through the apparatus, on line 7—7 of Fig. 1, showing the container in the normal position, and Fig. 8 is a view similar to Fig. 7, showing the container moved back from its normal position and articles being dispensed from the apparatus.

Referring to the drawings, 2 designates a box like frame or support comprising side walls 5 and front and back walls 8 and 9, respectively. This frame 2 may be supported in any convenient position by any suitable means, the means herein shown an arm or bracket 10 secured and extending upwardly from a table or counter 11 and having its upper end secured to the back wall 9.

of the frame 2 and supporting the frame 2 a suitable distance above the table 11 for a purpose hereinafter explained.

Rising fixedly from the forward portions 60 of the side walls 5 of the frame 2 are two standards 12 between which the container 13 for the articles 14 to be dispensed is located. The container 13 comprises a long cylindrical body portion 15 and a lower 65 cylindrical portion 16 having an annular flange 17 at its upper end within which the bottom of the body portion 15 is seated, the lower cylindrical portion 16 forming, in effect, a continuation of the body portion 15 70 and having an open bottom, as shown. The back of the lower portion 16 is secured to the lower portions of two bars 18 which are connected by a plate 19 back of the lower portion 16 of the container 13 and which extend parallel to the container, as shown. The upper end portions of the bars 18 are connected by and secured to a plate 20 which has a supporting part 21 secured thereto and embracing the body portion 15 of the 75 container 13 and extending more than half way around the container to retain it within the part 21. The body portion 15 of the container 13 is slidably fitted within the supporting part 21 to permit the body portion 15 to be withdrawn from the lower portion 16 of the container 13 and up through the part 21 when it is desired to remove the body of the container from the apparatus. The sides of the supporting part 80 21 are pivoted, at 22, to blocks 23 which are mounted to slide vertically in suitable guideways in the standards 12 and which are supported by screws 24 which extend through openings in the tops of the standards 12 and are screwed into the blocks 23. By turning the screws 24 the entire container 13 may be adjusted vertically with 85 respect to the frame 2 for a purpose hereinafter explained. 90 95 100

The container 13 is movable on its pivots 22 from the position shown in Figs. 2 and 7 to the position shown in Fig. 8 and back again, and it rests normally in the position shown in Figs. 2 and 7, returning thereto by gravity after being moved to the position shown in Fig. 8 and released. When the container 13 is in the normal position shown in Fig. 7, the lower open end of the container 13 is directly over and in registry with an annular receptacle 25 supported in the frame 2 and adapted to receive one or

more biscuits or other articles from the container 13, the container being proportioned, in the present instance to receive three articles or biscuits 14, as shown. The receptacle 25 has an open bottom and extending across its open bottom is a plate member 26 which is pivoted, at 27, to lugs extending downwardly from the receptacle 25, and which is movable on its pivots 27 from the 10 position shown in Fig. 7 to the position shown in Fig. 8, and back again, the member 26 falling by gravity to the position shown in Fig. 8, when it is permitted to do so. The member 26 is supported normally in the position shown in Fig. 7 by an arm 28 which is carried by and extends forwardly from a bracket 29 fixed to the lower ends of two arms 30 which extend downwardly from the back of the container 13 and are secured to 20 the plate 19 which connects the bars 18, so that the arm 28 and container 13 will move as a unit on the pivots 22. When the arm 28 and container 13 are moved from the position shown in Fig. 7 to the position 25 shown in Fig. 8, the arm moves from beneath the member 26 and permits it to fall on its pivots to the position shown in Fig. 8; and when the arm 28 and container 13 return by gravity to the position shown in 30 Fig. 7, the arm 28 engages the member 26 and raises it to its normal position shown in Fig. 7. Secured to the arm 28, and extending downwardly therefrom, is an arm 31 by means of which the arm 28 and container 13 may be moved back from the normal position shown in Fig. 7 to the position shown 35 in Fig. 8, as will be hereinafter explained.

Arranged between the arms 30 and extending between and secured to the back of 40 the receptacle 25 and the back wall 9 of the frame 2 is a floor plate 32 which forms, in effect, a continuation of the upper face of the receptacle 25 and is inclined upwardly and rearwardly therefrom. This plate 32 is 45 adapted to support the articles 14 within the container 13 when the container is moved back over the plate 32 to the position shown in Fig. 8.

The top of the container 13 is closed by a 50 suitable removable cap or cover 33 having a flange 34 which is fitted around the top of the container 13. The cover 33 is held in place by pins 35 which extend out through openings in the container 13 and aligned openings in the cover flange 34, and which are secured to the ends of a thin flat spring 36 which rests against the inner wall of the container 13 and extends part way around the same. By pressing the pins 35 55 inwardly against the action of the spring 36 to clear the pins 35 of the openings in the flange 34, the cover 33 may be removed from the container.

The front wall of the body 15 of the 60 container 13 has a vertical slot 37 therein which

is open at its top and which is adapted to receive the fingers and thumb of the hand of a person inserting the biscuits or other articles 14 into the container 13 and lowering them to the bottom thereof, when the cover 70 33 is removed. This slot 37 is normally closed by the glass panel 38 of a frame 39 which is held in the position shown on the front of the container 13 by a notched lug 40 on the bottom of the frame 39 embracing 75 a screw 41 on the container 13, back of the head of the screw, and by a lip or lug 42 on the cover 33 engaging the top and the forward face of the frame 39. When the cover 80 33 is removed from the container 13, the lug 42 frees the glass paneled frame 39 and permits the removal thereof from the container; and when the cover 33 is in place upon the container 13 the lug 42 holds the frame 39 in place.

To support the biscuits or other articles 14 horizontally within the body portion 15 of the container 13 while the container is being charged and before the articles 14 are permitted to drop into the lower portion 16 thereof, I provide a plate 45 which is adapted to be inserted into the lower portion of the body 15 of the container 13 through a slot 46 therein and to extend horizontally across the interior of the container, 90 as shown in Fig. 5; and this plate 45 is particularly useful when the body portion 15 of the container 13 is charged with the articles 14 while the body portion 15 is removed from the apparatus. After the body 100 15 has been charged and replaced within the apparatus, or after the body 15 has been charged while in the apparatus, the plate 45 is withdrawn from the container permitting the articles 14 stacked in the body 15 thereof to descend into the lower portion 16 thereof and into the receptacle 25 until the stack of articles rests upon the pivoted member 26, as shown in Fig. 7.

The forward portion of the lower portion 110 16 of the container 13 is provided with a brush 47, the upper portion of which is suitably secured to the container 13, and the lower portion of which is adapted to sweep across the top of the receptacle 25 and the article or articles 14 contained therein when the container 13 is moved back to the position shown in Fig. 8, and prevent more than the desired number of articles 14 from leaving the container 13.

The operation of the apparatus, briefly described, after the same has been charged with the articles 14, as previously explained, is as follows: When the container rests in its forward normal position, as shown in Figs. 2, 3 and 7, the container 13 is in registry with the receptacle 25, and the stack of articles 14 rests upon the pivoted member 26 which is supported in the position shown in Fig. 7 by the arm 28. When it is desired 120 130

- to dispense the article or articles within the receptacle 25, from the apparatus, the container 13 is moved from the normal position shown in Fig. 7, back to the position 5 shown in Fig. 8; and during such movement the articles 14 within the container 13 are moved back over the supporting plate 32 while the three lowermost biscuits or articles 14 of the stack remain in the receptacle 25, 10 being prevented from moving with the container 13 by the rear wall of the receptacle. During this back or rearward movement of the container 13 the articles 14 therein are moved back over and are supported by the 15 fixed floor plate 32; and, during this rearward movement of the container 13, the arm 28 moves back from beneath the pivoted member 26, permitting it to drop to the position shown in Fig. 8 and discharge the 20 three articles 14 from the bottom of the receptacle 25 by gravity, the pivots 27 of the member 26 being a sufficient distance back of the center of the receptacle 25 and the center of the articles within the receptacle 25 to insure the gravity discharge of the articles 14 from the receptacle. After the container 13 has been moved back to discharge the articles 14 from the receptacle and then 30 released, the container 13 returns to its normal position in registry with the receptacle 25 by gravity, and the stack of articles 14 within the container descends to and rests upon the member 26 whereupon the operation just described may be repeated. 35 Any suitable handle or operating arm may be connected to the container 13 or arm 31 and located in any convenient position to operate the apparatus. The arm 31 for this purpose, herein shown, is located to be 40 moved beneath the receptacle 25, so that when the hand of a person or a plate in the hand of a person is engaged with the arm 31 and moved beneath the receptacle 25, the container 13 and arm 31 will be moved back 45 to discharge the articles from the receptacle 25, and the discharged articles will fall into the hand of the person operating the apparatus or into the plate, as the case may be, as shown in Fig. 8. 50 By turning the screws 24 the entire container 13 may be adjusted vertically to bring the bottom of the container 13 and the bottom of its brush 47 into the proper relation to the top of the receptacle 25 and floor plate 55 32 to insure the deposit of the desired number of articles 14 into the receptacle 25 each time the apparatus is operated.
- I claim:
1. In a dispensing apparatus, the combination of a receptacle to receive the articles to be dispensed, a container having an open bottom and being movable to and from a position over and in registry with the receptacle, means to support the articles in 60 the container when it is away from its position over the receptacle, said receptacle having a fixed wall preventing an article within the receptacle from moving with the container when it is moved from its position over the receptacle, means to support an article within the receptacle and to permit it to fall therefrom when the container is moved from its position over the receptacle, and an arm extending downwardly from the receptacle below said wall, whereby a receiver passed under said receptacle may engage said arm and move the container from its position over the receptacle and thereby discharge an article from the receptacle into the receiver. 65
  2. In a dispensing apparatus, the combination of a receptacle to receive the articles to be dispensed, a container for said articles, the container having an open bottom and being movable to and from a position over and in registry with the receptacle, said receptacle supporting a stack of articles within the container with the lowermost article resting on a part of the receptacle when the container is in registry with the receptacle, and said receptacle having a fixed wall preventing an article in the receptacle from moving with the container when it is moved from its position over the receptacle, means to support the articles in the container when it is away from its position over the receptacle, and means to automatically discharge an article from the receptacle when said container is moved from its position over the receptacle. 75
  3. In a dispensing apparatus, the combination of a receptacle to receive the articles to be dispensed, said receptacle having an open bottom, a container for said articles, the container having an open bottom and being movable to and from a position over and in registry with the receptacle, means to support the articles in the container when it is away from its position over the receptacle, and movable means operatively connected to the container and preventing an article from falling from the receptacle when the container is over the receptacle and permitting an article to fall from the receptacle when the container is moved 80 from its position over the receptacle. 85
  4. In a dispensing apparatus, the combination of a receptacle to receive the articles to be dispensed, said receptacle having an open bottom, a container for said articles, the container having an open bottom and being movable to and from a position over and in registry with the receptacle, means to support the articles in the container when it is away from its position over the receptacle, a pivoted member movable from a position supporting an article within the receptacle to a position discharging an article from the receptacle, and means connected to the container and permitting said member 90 to discharge an article from the receptacle. 95
  5. In a dispensing apparatus, the combination of a receptacle to receive the articles to be dispensed, said receptacle having an open bottom, a container for said articles, the container having an open bottom and being movable to and from a position over and in registry with the receptacle, means to support the articles in the container when it is away from its position over the receptacle, a pivoted member movable from a position supporting an article within the receptacle to a position discharging an article from the receptacle, and means connected to the container and permitting said member 100 to discharge an article from the receptacle. 105
  6. In a dispensing apparatus, the combination of a receptacle to receive the articles to be dispensed, said receptacle having an open bottom, a container for said articles, the container having an open bottom and being movable to and from a position over and in registry with the receptacle, means to support the articles in the container when it is away from its position over the receptacle, a pivoted member movable from a position supporting an article within the receptacle to a position discharging an article from the receptacle, and means connected to the container and permitting said member 110 to discharge an article from the receptacle. 115
  7. In a dispensing apparatus, the combination of a receptacle to receive the articles to be dispensed, said receptacle having an open bottom, a container for said articles, the container having an open bottom and being movable to and from a position over and in registry with the receptacle, means to support the articles in the container when it is away from its position over the receptacle, a pivoted member movable from a position supporting an article within the receptacle to a position discharging an article from the receptacle, and means connected to the container and permitting said member 120 to discharge an article from the receptacle. 125
  8. In a dispensing apparatus, the combination of a receptacle to receive the articles to be dispensed, said receptacle having an open bottom, a container for said articles, the container having an open bottom and being movable to and from a position over and in registry with the receptacle, means to support the articles in the container when it is away from its position over the receptacle, a pivoted member movable from a position supporting an article within the receptacle to a position discharging an article from the receptacle, and means connected to the container and permitting said member 130 to discharge an article from the receptacle. 135

to move to its discharging position when the container is moved away from its position over the receptacle.

5. In a dispensing apparatus, the combination of a receptacle to receive the articles to be dispensed, said receptacle having an open bottom, a container for said articles, the container having an open bottom and being movable to and from a position over 10 and in registry with the receptacle, means to support the articles in the container when it is away from its position over the receptacle, a pivoted member movable from a position supporting an article within the receptacle to a position discharging an article from the receptacle, and an arm carried by the container and movable to and from a position beneath said member and permitting said member to move to its discharging position when the container is moved away 15 from its position over the receptacle and raising said member to its supporting position when the container is moved back to its position over the receptacle.
- 20 6. In a dispensing apparatus, the combination of a receptacle to receive the articles to be dispensed, a container for said articles, the container having an open bottom and being movable to and from a position over and in registry with the receptacle, means to support the articles in the container when it is away from its position over the receptacle, and means operative to move the container from its position over the receptacle 25 and to discharge articles from the bottom of the receptacle, said means including a downwardly extending arm movable beneath the receptacle and adapted to be moved by a device passed under the receptacle to receive the article discharged therefrom.

7. In a dispensing apparatus, the combination of a receptacle to receive the articles to be dispensed, a container for said articles, 30 said container being pivoted on the receptacle and having an open bottom and being movable on its pivot to and from a position over and in registry with the receptacle, said receptacle supporting a stack of articles within the container with the lowermost article resting on a part of the receptacle when the container is in registry with the receptacle, and said receptacle having a fixed wall preventing an article in the receptacle from moving with the container when it is moved from its position over the receptacle, and resting normally in said position, and means to support the articles in the container when it is away from its position 35 over the receptacle.

8. In a dispensing apparatus, the combination of a receptacle to receive the articles to be dispensed, a container for said articles, said container being pivoted on the receptacle and having an open bottom and being

movable on its pivot to and from a position over and in registry with the receptacle and resting normally in said position, said receptacle supporting a stack of articles within the container with the lowermost article resting on a part of the receptacle when the container is in registry with the receptacle, and said receptacle having a fixed wall preventing an article in the receptacle from moving with the container when it is moved from its position over the receptacle, means to support the articles in the container when it is away from its position over the receptacle, and means to automatically discharge an article from the receptacle when said container is moved from its position over the receptacle.

9. In a dispensing apparatus, the combination of a receptacle to receive the articles to be dispensed, said receptacle having an open bottom, a container for said articles, said container being pivoted on the receptacle and having an open bottom and being movable on its pivot to and from a position over and in registry with the receptacle and resting normally in said position, means to support the articles in the container when it is away from its position over the receptacle, and movable means operatively connected to the container and preventing an article from falling from the receptacle when the container is over the receptacle and permitting an article to fall from the receptacle when the container is moved away from its position over the receptacle.

10. In a dispensing apparatus, the combination of a receptacle to receive the articles to be dispensed, said receptacle having an open bottom, a container for said articles, said container being pivoted on the receptacle and having an open bottom and being movable on its pivot to and from a position over and in registry with the receptacle and resting normally in said position, means to support the articles in the container when it is away from its position over the receptacle, a pivoted member movable from a position supporting an article within the receptacle to a position discharging an article from the receptacle, and means connected to the container and permitting said member to move to its discharging position when the container is moved away from its position over the receptacle.

11. In a dispensing apparatus, the combination of a receptacle to receive the articles to be dispensed, said receptacle having an open bottom, a container for said articles, said container being pivoted on the receptacle and having an open bottom and being movable on its pivot to and from a position over and in registry with the receptacle and resting normally in said position, means to support the articles in the container when it is away from its position over the receptacle.

table, a pivoted member movable from a position supporting an article within the receptacle to a position discharging an article from the receptacle, and an arm carried by the container and movable to and from a position beneath said member and permitting said member to move to its discharging position when the container is moved away from its position over the receptacle and raising said member to its supporting position when the container is moved back to its position over the receptacle. 5

10 movable on its pivot to and from a position over and in registry with the receptacle and resting normally in said position, means to support the articles in the container when it is away from its position over the receptacle, and means operative to move the container from its position over the receptacle and to discharge articles from the bottom of the receptacle, said means including a downwardly extending arm movable beneath the receptacle and adapted to be moved by a device passed under the receptacle to receive the article discharged therefrom. 20 25

15 30

12. In a dispensing apparatus, the combination of a receptacle to receive the articles to be dispensed, a container for said articles, said container being pivoted on the receptacle and having an open bottom and being

In testimony whereof I have hereunto affixed my signature this sixth day of October, A. D. 1915.

OTTO JAEGER.
